434 N. Fulton Ave., Mount Vernon, N.Y.

Filed Aug. 26, 1960, Ser. No. 61,896

Term of patent 14 years

(Cl. D45—1)

FIG. 1

FIG. 2

FIG. 3

FIG. 1 is a top plan view of a gem mounting showing our new design;

FIG. 2 is a front elevational view thereof; and

FIG. 3 is a longitudinal cross-sectional view thereof.

The broken-line showing of a cuff-link in FIG. 3 is for illustrative purposes only.

The characteristic feature of our invention resides in a flat circular gem center section inlaid in a substantially flat oval gem base of contrasting surface reflectance, the whole being of substantial thickness and having a gem base support inlaid in the rear face thereof.

We claim:

The ornamental design for a gem mounting, substantially as shown and described.
